UNITED STATES PATENT OFFICE

97,266

DESIGN FOR A DRESS

Madeleine Croizat, New York, N. Y.

Application September 28, 1935, Serial No. 58,746

Term of patent 3½ years

To all whom it may concern:

Be it known that I, Madeleine Croizat, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The curved lines extending around the neckline above the yoke portion of the dress represent folds.

The irregular lines extending down from the ornamentation at the center of the yoke and extending up from the belt ornamentation, represent a fullness in the center of the waist portion of the dress.

The vertical lines extending down from the belt ornamentation represent the extensions of the sash, giving the appearance of a front panel on the skirt portion of the dress.

I claim:

The ornamental design for a dress, substantially as shown, and described.

MADELEINE CROIZAT.
